UNITED STATES PATENT OFFICE.

CHARLES ALEXANDER RAMSEY, OF ROSWELL, NEW MEXICO.

DESIGN FOR A PUTTY.

Application filed August 23, 1926. Serial No. 18,811. Term of patent 14 years.

To all whom it may concern:

Be it known that I, CHARLES ALEXANDER RAMSEY, a citizen of the United States, residing at Roswell, in the county of Chaves and State of New Mexico, have invented a new, original, and ornamental Design for Putty, of which the following is a specification, reference being had to the accompanying drawing, forming part thereof.

Figure 1 is a front elevation of a putty, showing my new design.

Figure 2 is a rear elevation of a putty, showing my new design.

I claim:

The ornamental design for a putty, as shown.

CHARLES ALEXANDER RAMSEY.
